(57) **CLAIM**

The ornamental design for an animal deterrent spiked-strip assembly, as shown and described.

DESCRIPTION

FIG. 1 is a front, top and left side perspective view of the animal deterrent spiked-strip assembly of the present invention;

FIG. 2 is a front, bottom and right side perspective view thereof;

FIG. 3 is a left side elevation view thereof;

FIG. 4 is a bottom plan view thereof;

FIG. 5 is a right side elevation view thereof;

FIG. 6 is an enlarged front elevation view thereof; and,

FIG. 7 is an enlarged rear elevation view.

The broken lines depicted for the tabs, tab recesses, and other apertures form no part of the claimed design.
